LEVER AND LINK FEED SLIDING JAW
WRENCH

Maurice A. Napier, Akron, Ohio

Application September 3, 1946, Serial No. 694,447

2 Claims. (Cl. 81--126)

1

This invention relates to wrenches, and more especially it relates to wrenches of the end opening type adapted for operation upon hexagonal nuts, couplings, screw heads and the like.

The invention is an improvement upon the wrench that constitutes the subject matter of my copending patent application, Serial No. 674,288, filed June 4, 1946, now abandoned.

Like the wrench of the copending application aforementioned, the wrench of the present invention is of especial utility for turning coupling nuts composed of relatively soft metal such as brass or lead. To this end the wrench is provided with the improved jaws of the prior application, which jaws are constructed and arranged to engage the work at three different points arranged 120 degrees apart; more specifically, the jaws are adapted to engage the alternate flat faces of a hexagonal nut or coupling. The wrench of the copending application is provided with two conventionally arranged handle members adapted to be manipulated by hand to grip and to release the work. The arrangement is such, however, that normal manipulation of said handles requires such an expansive opening of the operator's hand that use of the wrench is impracticable in close quarters where space is at a premium. It is to the relief of this condition that this invention primarily is directed.

The chief object of the invention is to provide in an improved manner for effecting the opening and closing of the jaws of wrenches of the character mentioned. More specifically the invention aims to provide a wrench whereof the jaws may be opened and closed with but little spreading of the operator's hand; and to provide a wrench whereof the force applied thereto to turn the work also clamps the jaws more firmly about the work. Other objects will be manifest as the description proceeds.

Of the accompanying drawing:

Fig. 1 is a side elevation of a wrench embodying the invention, and the work engaged thereby, showing how the wrench is grasped by the operator's hand;

Fig. 2 is a view of the structure shown in Fig. 1 when opened to the maximum extent, the head or fixed jaw of the wrench being sectioned on line 2-2 of Fig. 3; and

Fig. 3 is an edge elevation of the wrench viewed from the right of Fig. 2.

Referring to the drawing, there is shown a wrench comprising a head or fixed jaw 10, a movable jaw 11 carried thereby, a handle 12, and a link pivotally connecting said handle to said movable jaw. The fixed jaw 10 is a symmetrical one piece structure of irregular shape composed of heavy sheet metal, said structure being bent or folded along the centerline thereof to provide identical lateral portions 10a, 10a that are disposed in parallelism, and in slightly

2

spaced relation to each other to receive the movable jaw 11 that is located therebetween. Adjacent the lower end of the structure 10, at the rear thereof, the lateral portions 10a are formed with respective axially aligned apertures in which a headed pin or rivet 14 is received, the handle 12 being pivotally mounted at its upper end on said rivet, between lateral portions 10a. At the bottom of structure 10, and at the front thereof (which is at the right as shown in Figs. 1 and 2), the lateral portions 10a are formed with relatively short obliquely downwardly extending portions 15, 15. The respective upper margins of the latter, and the front margins of the portions 10a adjacent thereto, are formed with integral flanges 16, 16 that are bent toward each other and abut each other in edge-to-edge relation in the central plane of the wrench, as is clearly shown in Fig. 3.

At its upper end, the medial fold or bend of the fixed jaw 10 terminates at 18, the lateral portions 10a extending therebeyond and extending toward each other into abutting relation, where they are permanently secured to each other as by welding. The region where the portions 10a are welded to each other constitutes a nose 19, which nose overhangs that portion of the jaw immediately therebelow, the bottom margin of said nose being flat and constituting a work engaging surface 20.

Positioned between lateral portions 10a of the fixed jaw 10 is the movable jaw 11 arranged for sliding movement toward and away from the nose 19, the rear margin of said movable jaw abutting the medial fold or bend of the fixed jaw, the front margin thereof being flush with the front margin of said fixed jaw. The movable jaw is formed with a slot 23 that is parallel to the front and rear margins of the jaw, and a rivet 24 extending from one lateral portion 10a to the other extends through said slot and limits the operative movement of the movable jaw.

Movement of the jaw 11 relatively of the fixed jaw 10 is effected by the handle 12 to which said movable jaw is pivotally connected by a link 25. The latter is of dumb-bell contour, its generally circular end portions being received in complementally shaped sockets in the jaw 11 and handle 12. The socket in the jaw 11 opens onto the bottom margin thereof, and the socket in the handle 12 opens onto the upper margin thereof, forwardly of the pivot pin 14. The arrangement is such that angular movement of the handle on its pivot 14 effects longitudinal movement of the jaw 11. The link 25, movable jaw 11, and handle 12 are all of the same thickness and are disposed in the same plane. The top margin of the movable jaw 11 is formed with a V-shape recess or notch, the diverging walls or faces 27, 28 of which are arranged at an angle of exactly 60 degrees to each other. In the assem-

bled structure, faces 27,28 also are disposed at exactly 60 degrees to the face 20 of the fixed jaw 10. The fixed jaw is recessed below the face 20 to such an extent that faces 27,28 of the movable jaw always are disposed exteriorly of the fixed jaw.

The arrangement is such that a hexagonal nut or coupling member, such as shown at 30, Fig. 1, may be engaged by the fixed jaw and the movable jaw of the wrench, with the faces or margins 27, 28 engaging two of the flat sides or faces of the nut or coupling and the face or margin 29 engaging the third side thereof. It will be observed that the wrench engages alternate sides of the nut or couplings, which sides are 120 degrees apart from each other.

The manner of grasping the wrench to operate the same is clearly shown in Fig. 1. As shown, the handle 12 is grasped in the hand with the forefinger thereof hooked over the obliquely extending portions 15 of the wrench, as in handling a gun trigger. When the wrench is engaged with a nut or coupling 30 as shown, it is only necessary to urge the handle in counter-clockwise direction to cause the wrench to grip the nut or coupling and to turn the same. When it is desired to reverse the movement of the wrench to obtain a new grip on the work, it is only necessary to release the pressure of the forefinger, and move the handle in the opposite direction, thereby opening the jaws of the wrench sufficiently so that they will pass the corners of the hexagonal nut or coupling, as shown in Fig. 2. Such movement of the handle is relatively small, being through an arc of about 10 degrees as will be apparent from a comparison of the position of the handle in Fig. 1 and in Fig. 2. Accordingly, the forefinger requires to be loosened or moved only a trifling extent to enable the handle to be moved as described, thus adapting the wrench for use in tight situations where a more expansive opening of the hand would be impossible. This is true whether the wrench is engaged with work of the maximum size for which it is designed, or work of minimum size. The slot 23 allows substantial range of movement of the movable jaw 11, so that the wrench is adapted to operate upon hexagonal work pieces of several different standard sizes.

The wrench is simple in construction, and may be made from stamped parts, thus reducing the cost thereof. The wrench may be used in situations where wrenches with widely opening handles could not be employed. The link 25 that connects the handle 12 to the movable jaw 11 is subjected only to compressive stress during the tightening of the work, and therefore is capable of withstanding great strain without buckling, flexing, or other deformation. The wrench is readily capable of use in a manner that achieves the function of a ratchet wrench, and it accomplishes the other objects set out in the foregoing statement of objects.

Modification may be resorted to without departing from the spirit of the invention, or the scope thereof as defined by the appended claims.

What is claimed is:

1. A wrench of the type having a fixed jaw and a movable jaw, said fixed jaw comprising a symmetrically shaped plate folded along its center line and with its sides arranged in parallelism in spaced relation throughout the major portion of the fixed jaw and being in contact throughout a relatively small outer portion to constitute an abutment for a nut to be engaged, a movable

jaw disposed between the said spaced sides of said fixed jaw and adapted to move toward and from said abutment, means limiting the extent of motion of said movable jaw, a handle permanently pivoted between said spaced sides of said fixed jaw, a connecting link pivotally attached to said movable jaw and said handle, the pivot point of said handle being, in all positions of adjustment of said movable jaw, appreciably spaced from a line between the pivotal centers of said connecting link and substantially laterally adjacent the pivotal center of the link in the handle in the mean position of the movable jaw whereby to impart rapid motion to said movable jaw, and an extension on said fixed jaw directed obliquely to the path of motion of said movable jaw and being appreciably shorter than said handle whereby one or more fingers of the hand may engage the said extension, trigger fashion, and swing the same throughout large angular motion without interference by the balance of the fingers engaging the said handle.

2. A wrench of the type having a fixed jaw and a movable jaw, said fixed jaw comprising a symmetrically shaped plate folded along its center line and with its sides arranged in parallelism in spaced relation throughout the major portion of the fixed jaw and being in contact throughout a relatively small outer portion to constitute an abutment for one side of a nut to be engaged, a Y-shaped movable jaw disposed between the said spaced sides of said fixed jaw and adapted to move toward and from said abutment, means limiting the extent of motion of said movable jaw, a handle permanently pivoted between said spaced sides of said fixed jaw, a connecting link pivotally attached to said movable jaw and said handle, the pivot point of said handle being, in all positions of adjustment of said movable jaw, appreciably spaced from a line between the pivotal centers of said connecting link and substantially laterally adjacent the pivotal center of the link in the handle in the mean position of the movable jaw whereby to impart rapid motion to said movable jaw, and an extension on said fixed jaw directed obliquely to the path of motion of said movable jaw and being appreciably shorter than said handle whereby one or more fingers of the hand may engage the said extension, trigger fashion, and swing the same throughout large angular motion without interference by the balance of the fingers engaging the said handle.
